UNITED STATES PATENT OFFICE.

ANNIE M. DITTLER, OF OAKDALE, PENNSYLVANIA.

DESIGN FOR A COOKING UTENSIL.

SPECIFICATION forming part of Design No. 34,421, dated April 23, 1901.

Application filed March 27, 1901. Serial No. 53,149. Term of patent 14 years.

To all whom it may concern:

Be it known that I, ANNIE M. DITTLER, a citizen of the United States of America, residing at Oakdale, in the county of Allegheny and State of Pennsylvania, have invented and produced a certain new and original Design for a Cooking Utensil, of which the following is a specification, reference being had therein to the accompanying drawings.

Figure 1 is a detail perspective view of a cooking utensil, showing my new design. Fig. 2 is a transverse vertical sectional view of the same.

As shown in the drawings, the leading or material feature of my design consists in the substantially cylindrical body 1, the bottom 2 of which is some distance above the lower end of the cylindrical body and the lower end of which body is provided with arched cut-

away portions 3. At its upper end this cylindrical body is provided with ornamental scrollwork 4, and extending upwardly and outwardly in the curved direction is a handle 5, the upper face of which carries fanciful scrollwork 6 and near the end of which handle is an opening 7.

Having thus fully described my invention, what I claim as new, and desire to secure by Letters Patent, is—

The design for a cooking utensil, as herein shown and described.

In testimony whereof I affix my signature in the presence of two witnesses.

ANNIE M. DITTLER.
